CLAIM

The ornamental design for a half arch toy brick as shown and described.

DESCRIPTION

FIG. 1 is a first top perspective view of a half arch toy brick. FIG. 2 is a first bottom perspective view of the half arch toy brick.

FIG. 3 is a second top perspective view of the half arch toy brick. FIG. 4 is a second bottom perspective view of the half arch toy brick.

FIG. 5 is a first end plan view of the half arch toy brick.

FIG. 6 is a second end plan view of the half arch toy brick.

FIG. 7 is a front plan view of the half arch toy brick.

FIG. 8 is a back plan view of the half arch toy brick.

FIG. 9 is a top plan view of the half arch toy brick.

FIG. 10 is a bottom plan view of the half arch toy brick.

FIG. 11 is a first top perspective view of a second embodiment of the half arch toy brick.

FIG. 12 is a first bottom perspective view of the second embodiment of the half arch toy brick.

FIG. 13 is a second top perspective view of the second embodiment of the half arch toy brick.

FIG. 14 is a second bottom perspective view of the second embodiment of the half arch toy brick.

FIG. 15 is a first end plan view of the second embodiment of the half arch toy brick.

FIG. 16 is a second end plan view of the second embodiment of the half arch toy brick.

FIG. 17 is a front plan view of the second embodiment of the half arch toy brick.

FIG. 18 is a back plan view of the second embodiment of the half arch toy brick.

FIG. 19 is a top plan view of the second embodiment of the half arch toy brick; and,

FIG. 20 is a bottom plan view of the second embodiment of the half arch toy brick.

The broken lines in the figures show features of the half arch toy brick that form no part of the claimed design.
